UNITED STATES PATENT OFFICE.

HARRY P. LEWIS, OF OTTAWA, ONTARIO, CANADA.

SWITCHING DEVICE.

1,408,613.

Specification of Letters Patent.

Patented Mar. 7, 1922.

Application filed February 11, 1921. Serial No. 444,277.

To all whom it may concern:

Be it known that I, HARRY P. LEWIS, a subject of the King of the United Kingdom of Great Britain and Ireland, residing 5 at Ottawa, Province of Ontario, Dominion of Canada, have invented certain new and useful Improvements in Switching Devices, of which the following is a specification.

This invention relates to switching devices for switch-points used in connection with railway tracks, the same being of the type in which the motorman of a car can operate a plunger thereon which is adapted to contact with the switching device to 10 swing the switch-point to the right or to the left, according to the direction which the motorman wishes his car to take. The present invention is particularly useful in connection with electric railways, and preferably 15 comprises purely mechanical mechanism. One of the objects of the invention is to provide a simple mechanical switching device, which consists of comparatively few parts, considering the functions which the 20 device performs and the manner in which it performs those functions. Another object is to provide a switching device which is adapted to operate in all kinds of weather and after long exposure to the elements. 25 Another object of the invention is to provide a switching device which is adapted to operate in brine during the winter months and which can be drained in summer. Other objects of the invention are to provide a 30 comparatively inexpensive device which is not only safe for the railways, but for pedestrians.

These being among the objects of the present invention the same consists of certain 35 features of construction and combinations of parts to be hereinafter described and then claimed with reference to the accompanying drawings illustrating a desirable embodiment of the invention, in which—

40 Fig. 1 is a plan view of the cover or top plate below which the switching mechanism proper is arranged;

Fig. 2 is a plan view of a part of the cover showing the switching mechanism, 45 partly in full, and partly in dotted lines in connection with a switch-point;

Fig. 3 is a sectional elevation of parts carried by the car in connection with the switching mechanism proper;

Fig. 4 is a section of the plunger device 55 on the car transversely to Fig. 3; and

Fig. 5 is an end elevation, partly in section, showing how a switch-point is connected with the device.

Referring to Figs. 2 and 3, a box or casing 10 has suitably mounted therein the gear train of the switching device, which gear train comprises a shifting-member 11 provided with a segmental series of spur-teeth 12. The spur-teeth 12 are constantly in mesh 60 with the spur-teeth 13 of a wheel 14, the said wheel and the member 11 constituting two intermeshed shifting-members which are respectively mounted upon parallel 65 shafts 16, 17, which turn in suitably removable bearings or boxes in the casing 10. Secured to one face of the wheel 14, as by riveting or welding, is a disk 18, or they may be made as one integral structure. The 70 wheel 14 and the disk 18 may be said to constitute another shifting-member, and the shifting-member 11 and the member 18 are adapted to be rotated in parallel vertical 75 planes. A segmental or mutilated gear 13 will be located to one side of the diameter 80 of the wheel 14, while at the other side of said diameter the wheel 14 is provided with a segmental series of crown or mitre teeth 19, which project to one side of the plane of the shifting-member 11 and said wheel 14, 85 that is, away from the disk or member 18.

A bearing 20 is supported in the casing 10, and one end of a jack-shaft 21 is journaled therein. The inner end of the jack-shaft 21 carries a wheel 22 provided with a 90 segmental series of crown or mitre teeth 23, and these teeth are in mesh with the teeth 19 of the shifting-member 14, 18. The jack-shaft 21 extends away from the direction 95 from which the car is to operate the switch, and is preferably protected by a covering 24 which is pinned or otherwise secured to shaft 21. The shaft 21 and the covering 24 are 100 preferably made of metal tubing, the covering having a sufficiently snug fit upon said shaft. The outer end of the shaft 21 is provided with a crank-arm 25, to which is pivotally connected one end of a rod 26, which extends transversely of the line of track, the other end of said rod being suitably secured to the movable switch-point 27.

Switch-point 27 is associated with any well-known construction of track, so that when 105

shifted, a car may pass in the direction desired.

On the edge of the shifting-member 11 is a tripping-lug 28, and on the edge of the disk 18 there is another tripping-lug 29. The lug 29 is in effect a projection from the duplex gear-wheel 14, and the two lugs 28, 29 are so arranged that when one of the lugs is moved to stand upright the other lug will 10 be inclined with respect thereto.

Referring to Fig. 1, a cover-plate in two sections 30, 31 is illustrated, these two plates being suitably joined together at their meeting ends 32, preferably so that a part of one 15 plate will set into a recess in the other plate, as shown. The car approaches from the direction indicated by the arrow in Fig. 1, and the cover-plate 31 is in advance of the plate 30 which constitutes the cover for the casing 20 10, it being suitably secured thereto. The two plates 30, 31 lie in one horizontal plane, and the top surfaces thereof are roughened or corrugated as at 33, 34, or provided with 25 carks to prevent slipping thereon of horses, etc. Preferably, the upper surfaces of the cover-plates 30, 31 are constructed as follows: The flaring entrance throat or recess 30 is provided in the approach end of plate 31, and the bottom of said throat inclines 30 downwardly from the end edge of said plate, to the forwardly-extended pointed end 36 of a longitudinal rib 37 on the plates 30, 31, at opposite sides of which rib are grooves 38, 39. Plate 30 is provided with two longitudinal slots 40, 41, which are in line with the grooves 38, 39, being located in the bottoms of said grooves. One of the slots, as, for instance, slot 40, is located in advance of the other slot. Those portions of the grooves 40 38, 39 which are located to the rear of the slots 40, 41, are inclined upwardly, away from the slots to the top surface of plate 30. When the cover-plate 30 is mounted on the casing 10, the slots 40, 41 will be positioned, 45 respectively, over the member or disk 18 and the member 11, so that the tripping-lug of each may be moved to be protruded through its slot, or to be moved downwardly from the slot. The sloping bottoms of the throat 50 35 and the grooves 38, 39, provide respectively for the engagement of the operating members of the car with the grooves, and disengagement therefrom, and the grooves also provide for the tripping of one of the lugs 28, 29, depending upon which of the operating members on the car is operated. The cover-plate 30 may be provided with a handle 42 to assure convenience of removal of said plate. It is preferred that the jack-shaft 21 be considerably elongated, say, to 60 65 eight (8) feet, to insure that the motorman sees that the switch is really thrown before he reaches it.

The preferred means for operating the 65 switching device is illustrated in Figs. 3 and

4. In these figures a portion 43 of a car is shown, the same having for convenient access by the motorman, two plungers 44, 45, which are normally raised by springs 46. One of these plungers is a right-hand plunger, and the other a left-hand plunger. Assuming that the motorman of a car desires to go straight ahead or keep to the left of the switch-point 27, he will then depress the right-hand plunger 45 sufficiently to cause 75 it to enter the throat 35 and into the groove 39. This depression suffices to bring the lower end of the plunger 45 into contact with the upstanding lug 28, and as the car travels, this movement will cause the said 80 plunger to shift the lug 28 downwardly and to impart a partial revolution to the shifting-member 11, bringing said member and its lug into the position illustrated in Fig. 3. This partial revolution of member 11 will 85 cause the teeth 12 to turn the teeth 13 and the wheel 14 carrying them in opposite direction, which will furthermore cause the teeth 19 which intermesh with the teeth 23, to turn the jack-shaft 21 in such direction 90 as to move the crank-arm 25 towards the right-hand, and hence, to similarly move the switch-point 27, so that the through track is clear, or the car will go to the left.

Due to these movements of the gear-train, 95 the lug 29 will be projected up through its slot, as shown in Fig. 3.

Obviously, if the motorman desires to go to the right he will depress that plunger which, when lowered, will engage the upstanding tripping-lug 29, whereupon the 100 train of mechanism is operated so as to swing the switch-point 27 over to the left.

The described switching device is positive in its action, and being preferably wholly 105 mechanical, it is obvious that it will operate, even though the casing or box 10 is partly filled with sand or earth, as the gearing will simply grind therethrough.

The above described invention is obviously susceptible to more or less modification, without departing from the invention as defined in the appended claims.

Having thus described my invention, what I claim as new is:

1. In a switching device, the combination of a switch-point, parallel rock-shafts, a shifting member mounted on one of said shafts transversely thereof and having a series of spur-teeth, and a tripping-lug at 120 one end of the said series of teeth, a second shifting member mounted on the other shaft transversely thereof, and having a segmental series of spur-teeth in mesh with aforesaid series, and also having a tripping-lug 125 at one end of its series of teeth, the two lugs being spaced laterally apart to turn in two different planes, and the second shifting member also having a segmental series of crown-teeth, the two series of teeth on the 130

second shifting member being located at opposite sides of the shaft which carries said second member, and a jack-shaft connected with the switch-point and having a gear with a segmental series of crown-teeth in mesh with aforesaid crown-teeth.

2. In a switching device, the combination of a switch-point, parallel rock-shafts, a shifting member mounted on one of said shafts transversely thereof and having a segmental series of spur-teeth, and a tripping-lug at one end of the said series of teeth, a second shifting member mounted on the other shaft transversely thereof to turn in the same plane as the other shifting member, and having a segmental series of spur-teeth in mesh with aforesaid series, and also having a tripping-lug at one end of its series of teeth, the two lugs being spaced laterally apart to turn in two different planes, and the second shifting member also having a segmental series of crown-teeth, the two series of teeth on the second shifting member being located at opposite sides of the shaft which carries said second member, and a jack-shaft connected with the switch-point and having a gear with a segmental series of crown-teeth in mesh with aforesaid crown-teeth.

3. In a switching device, the combina-

tion of a cover plate provided with parallel slots, one in advance of the other, a switch-point, shifting-members mounted below said plate for rotation in substantially parallel planes and having tripping-lugs opposite said slots adapted to be turned, a jack-shaft connected with the switch-point, and gear means combined with said shifting-members and jack-shaft for projecting one of said lugs through its slots as the lug is tripped, said gear means comprising two segmental series of intermeshing spur teeth on said shifting-members and two segmental series of intermeshing crown or mitre teeth on one of said shifting-members and said jack-shaft.

4. In a switching device, a cover-plate having an advanced flaring throat with a downwardly inclined bottom, and a rib extending longitudinally of said cover-plate, between two grooves in said plate, said rib having a forwardly-extended pointed end, located in the rear of said downwardly-inclined bottom, and said plate having two slots, one in advance of the other in the bottom of said grooves, and the bottoms of said grooves to the rear of said slots inclining upwardly.

HARRY P. LEWIS.
